(57) CLAIM

The ornamental design for an “implant inserter,” as shown and described.

DESCRIPTION

FIG. 1 is a perspective view of one embodiment of an implant inserter which embodies my new and original design therefor;

FIGS. 2 and 3 are top and bottom plan views thereof, respectively;

FIGS. 4 and 5 are front and rear end elevational views thereof, respectively; and,

FIG. 6 is a right side elevational view thereof, the left side elevational view being a mirror image thereof.
